UNITED STATES PATENT OFFICE.

JOHN N. REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

AUTOMATIC TELEPHONE SWITCH.

Application filed July 21, 1921. Serial No. 486,367.

To all whom it may concern:

Be it known that I, JOHN NEWBERRY REYNOLDS, a citizen of the United States, residing at Greenwich, in the county of Fairfield,

5 State of Connecticut, have invented certain new and useful Improvements in Automatic Telephone Switches, of which the following is a full, clear, concise, and exact description.

10 This invention relates to switching apparatus for use in automatic telephone exchange systems and the like, and more particularly to an improved form of cross bar switch, its object being simplicity and reliability of operation and economy in manufacture and maintenance.

15 For simplicity of disclosure the invention is herein described as a line switch for making connection between any one of a 20 number of incoming lines and one of a number of outgoing lines.

25 It is adaptable to the switching system disclosed in the British Patent No. 183,438, issued to Western Electric Company Limited, accepted September 6, 1923, and, as will be apparent to those skilled in the art, is capable of wide application in automatic switching systems generally.

30 The invention in its broader aspects comprises coordinate rows of stationary and movable contact member groups with selectively controlled operating mechanism whereby each group of movable contact members may be brought into electrical contact with any group of stationary contact members, the actuating mechanism being so formed as to produce a substantial rubbing action on each contact member.

35 Both sets of contact members are preferably in the form of bare wires, the stationary wires being supported in the form of an open grid on transverse strips of insulation, the movable wires extending through said grid and normally held out of contact with the wires thereof by means of a plurality of small cards of insulation, one of which is individual to each movable contact group.

40 Selecting and operating mechanism is provided whereby any card may be moved independently of the others to bring its associated wires into engagement with the adjacent grid wires.

45 In the case of a line switch, for example, a plurality of trunk bars are provided, each 50 of which is associated with a row of flexible

contact wires or springs. Each trunk bar has a plurality of laterally extending flexible arms, one for each set of associated contact springs. The trunk bars together with the laterally extending arms are rotatable 60 through a small angle by individual electromagnets or by other suitable operating means.

Upon rotation of a trunk bar out of its 65 normal position, the free end of each laterally extending arm thereon is moved into operative position with respect to one of the cards above mentioned through which the several contact springs comprising each set extend.

70 Associated with each set of line conductors in the grid is a line bar extending at right angles to the trunk bars and provided with a plurality of laterally extending rigid arms, each of which is associated with one of the 75 flexible arms of a trunk bar and adapted to engage the latter upon conjoint operation of the respective trunk and line bars. The line bars together with their laterally extending arms are likewise rotatable in response to the energization of an electromagnet, one of which is provided for each line bar.

75 Other features of invention will appear from the detailed description given below 80 in connection with the accompanying drawings.

In the drawings, Fig. 1 is a perspective view of a portion of the switch, certain parts being omitted for the sake of clearness. Fig. 90 2 is a cross sectional view taken at right angles to the grid conductors and Fig. 3 is a detail view of one of the flexible trunk bar arms.

85 The sets of grid conductors comprising 95 the wires 1, 2, 3, 4 and 1', 2', 3', 4' etc., are securely fastened at their ends to fixed members, not shown, and are preferably woven in and out between the insulating strips 5, as shown in Fig. 1.

100 Supports 6 and 7 are of insulating material, and are disposed at right angles to the direction of the length of the grid conductors, and on them are mounted the flexible wire contact springs 8, 9, 10, 11 and 8', 9', 10', 11', etc. The supports 6 and 7 may be of considerable length and may carry any desired number of sets of contact springs 8, 9, 10, 11, etc., depending upon the switch capacity desired. For simplicity of illus- 110

tration, however, only two such sets are shown on each of the supports in the partial view of Fig. 1 and six sets on the view shown in Fig. 2. The free ends of each set of contact springs 8, 9, 10, 11, etc., extend through oblique apertures 12' in a tie member or card 12, each of which is mounted on flat springs 13 and 14, said flat springs being fixed at one end portion to the support 6. The free end 13' of spring 13 is bent to a Z shape and normally rests on the topmost conductor of its associated set of grid conductors. The springs 13 and 14 are adjusted normally to hold the cards 12 and contact springs down out of contact with the grid conductors.

In Fig. 1, there are shown only two supports 6 and 7, but in practice, there would be a number of these bars depending upon the switch capacity desired.

Individually associated with each of the supports 6 and 7 is a bar 15 which is journaled at its end portions in bearings not shown. Securely attached to each bar 15 is an armature 16 which is arranged to be attracted by electromagnet 17 whereby the bar 15 is rotated through a small angle.

In the case of a line switch chosen for illustrating the invention, the springs or wires 8, 9, 10, 11, and 8', 9', 10', 11', etc., of one vertical row are connected in multiple and form multiple terminals of a set of trunk conductors, while each set of horizontal wires 1, 2, 3, 4 in the grid form the terminals of a set of subscribers' line conductors.

The energization of an electromagnet 17 associated with a given set of trunk conductors, sets that trunk for seizure by the next subscriber's line calling as follows: The armature 16 is attracted thereby rotating the bar 15 to move all of the rods 23 carried thereby into position beneath the cards 12 which support the various groups of multiple trunk terminals 8, 9, 10, 11, and 8', 9', 10', 11', etc., belonging to that trunk.

When a subscriber calls, the magnet 26', for example, individual thereto will be energized and by attracting its armature 25' will rotate the line bar 24'. This rotation raises all the operating arms 27' carried by the line bar. The arm 27' which is located at the point of crossing of the line bar 24' and the trunk bar 15 of the trunk which has been set for seizure will, on being raised, encounter the selecting rod 23 which is in position beneath the card 12 at that point, and will raise the card forcing the conductors 8', 9', 10', and 11' into engagement with the line conductors 1', 2', 3' and 4' respectively. The card 12 is provided with diagonal slots 12' so that a lateral sliding action is produced on the grid conductor which insures a clear and reliable contact. Owing to the diagonal arrangement of the grid con-

ductors resulting from its woven construction there is also produced a longitudinal rubbing action on the flexible conductors 8', 9', 10' and 11', giving further assurance of a good connection.

After the above operation, the continued energization of the line magnet 26' maintains the connection between the line and trunk conductors.

The trunk magnet 17 may, however, be deenergized without destroying the connection inasmuch as the notched terminal of the operating arm 27' holds the rod 23 positioned in the notch 12' of the card 12. Furthermore, the rod 23 being flexible, trunk bar 15 can return to normal under the influence of spring 18. This feature is important in some applications of the switching structure of this invention in that it permits a second actuation of the trunk bar without disturbing the existing connection.

What is claimed is:

1. In a switching mechanism, a plurality of sets of conductors arranged in parallel rows, a plurality of sets of movable contact members arranged in rows coordinate to said rows of conductors, a plurality of sets of movable contacts corresponding to and having their ends extending through said movable contact members, each of said movable contact sets being adjacent to one of said sets of conductors, a selecting bar for each row of movable contact members, a plurality of arms on each of said selecting bars, said arms associated with said movable contact members individually, but normally out of operable relation therewith, means for operating said selecting bars individually to move said arms into operable relation with their respectively associated movable contact members, and means including said arms for individually operating said movable contact members to effect engagement between said contact sets and the adjacent conductors.

2. In a switching mechanism, a plurality of sets of stationary conductors, a plurality of rows of movable contact members disposed coordinately to said stationary conductors, a plurality of rows of movable contacts corresponding to and having their ends extending through said movable contact members, each of said rows of movable contacts divided into a plurality of sets, and each set of each row associated with a different set of stationary conductors, a rotatable bar for each row of movable contact members, a plurality of laterally extending arms on each of said bars, each of said arms associated individually with one of said movable contact members, means for rotating said bars individually, other rotatable bars, each individual to one of said sets of stationary conductors, a plurality of laterally extending arms on each of said last

mentioned bars, means for rotating said last mentioned bars, the conjoint rotation of any one of said first mentioned bars and any one of said last mentioned bars being effective to move one of said members to in turn move a set of said movable contacts into engagement with its associated stationary conductors.

3. In a switching mechanism, a plurality of sets of fixed conductors arranged in an open grid, a plurality of sets of movable conductors arranged in rows at right angles to said grid conductors and extending through said grid, each movable conductor crossing one of said grid conductors but normally out of contact therewith, a selecting bar individual to each row of movable conductor sets, an operating bar individual to each set of grid conductors, means for actuating said bars individually, and means whereby the conjoint actuation of one of said selecting bars and one of said operating bars establishes a connection between a set of movable conductors and a set of grid conductors at their crossing point.

4. In a switching mechanism, a plurality of sets of fixed conductors arranged in an open grid, a plurality of sets of movable conductors arranged in rows at right angles to said grid conductors and extending through said grid, a movable support for each set of movable conductors normally maintaining said conductors out of contact with the grid conductors, a selecting bar individual to each row of movable conductors, an operating bar individual to each set of grid conductors, and means acting on said support and brought into operation by the conjoint actuation of one of said selecting bars and one of said operating bars to move the conductors supported thereby into engagement with a set of grid conductors.

5. In a switching mechanism a fixed contact bank comprising a plurality of sets of parallel conductors, a plurality of sets of movable conductors arranged in rows at right angles to said bank conductors and extending through said bank, each movable conductor crossing one of said bank conductors but normally out of contact therewith, a movable support for each set of movable conductors, a selecting bar common to each row of movable conductors, a selecting arm on said bar individual to each movable support in said row, an operating bar common to each set of bank conductors, an operating arm thereon for each set of movable conductors crossing said set of bank con-

ductors, means for actuating a selecting bar to bring its selecting arms into position for operating the movable supports individual to said bar, means for actuating an operating bar to bring its arms into cooperative relation with those of its associated selecting arms which have been moved to operating position, the conjoint actuation of one of said selecting bars and one of said operating bars serving to establish a connection between a set of movable conductors and a set of bank conductors at their crossing point.

6. In a switching mechanism, a plurality of rows, each comprising a plurality of sets of contact springs, rows of sets of fixed conductors disposed coordinately to said first mentioned rows, each of said sets of contact springs associated with one of said sets of fixed conductors, a tie member for each of said sets of contact springs, a bar associated with each of said first mentioned rows, a plurality of arms on said bar each associated with one of said tie members but normally out of operable relation thereto, means for operating said bars individually for moving said arms into operable relation to said tie members, other bars, each individual to one of said rows of fixed conductors, a plurality of arms on each of said last mentioned bars, means for operating said last mentioned bars individually, each of said last mentioned arms being associated with one of said first mentioned arms and adapted to engage the latter and move it together with its associated tie member to effect the contact of its associated springs with a set of fixed conductors.

7. In a switching mechanism, a plurality of sets of fixed conductors arranged in an open grid, a plurality of sets of movable conductors arranged in rows at right angles to said grid conductors and extending into said grid, each movable conductor being associated with one of said grid conductors but normally out of contact therewith, a selecting bar individual to each row of movable conductor sets, an operating bar individual to each set of grid conductors, means for actuating said bars individually, and means whereby the conjoint actuation of one of said selecting bars and one of said operating bars establishes a connection between a set of movable conductors and a set of grid conductors.

In witness whereof, I hereunto subscribe my name this 20th day of July A. D., 1921.

JOHN N. REYNOLDS.
